J. VLACH JR. INVENTOR.

BY

John Randolph Jr.

ATTORNEY.

UNITED STATES PATENT OFFICE.

JOSEPH VLACH, JR., OF HANOVER, KANSAS.

HAM-HANGER.

1,378,739.

Specification of Letters Patent. Patented May 17, 1921.

Application filed April 14, 1920. Serial No. 373,827.

To all whom it may concern:

Be it known that I, JOSEPH VLACH, Jr., a citizen of the United States, residing at Hanover, in the county of Washington and 5 State of Kansas, have invented certain new and useful Improvements in Ham-Hangers; and I do hereby declare the following to be a full, clear, and exact description of the invention, such as will enable others skilled 10 in the art to which it appertains to make and use the same.

This invention relates to new and useful improvements in ham hangers especially adaptable for supporting hams either on 15 display or while being smoked and has for its primary object the provision of a supporting element and an attaching member having one end pivoted to the element and its other end detachably connected thereto 20 so that said member may be easily and quickly passed through the opening in the shank of a ham and then secured to said supporting element and retained in connection therewith by the weight of the ham, thereby 25 obviating the danger of the ham falling or becoming detached which is frequent when hams are supported by strings.

Another object of this invention is the provision of a ham hanger of the above 30 stated character which shall be simple, durable and efficient, and which may be manufactured and sold at a comparatively low cost.

With these and other objects in view as 35 will become more apparent as the description proceeds, the invention consists in certain novel features of construction, combination and arrangement of parts as will be hereinafter more fully described and 40 claimed.

For a complete understanding of my invention, reference is to be had to the following description and accompanying drawing, in which:—

45 Figure 1 is a side elevation illustrating a ham hanger constructed in accordance with my invention and applied to a ham,

Fig. 2 is an end elevation illustrating the same.

50 Referring in detail to the drawing, the numeral 1 indicates a supporting element constructed from a single length of material or heavy wire which has one end bent to form an eye 2 while its other end is bent 55 to form a loop 3 adapted to receive or be

placed over a support or hook. The heavy wire after being bent to form the loop 3 is twisted about the shank 1 as illustrated at 4 and then bent outwardly and upwardly from said shank to form a hook or catch 5. 60

A substantially arcuate shaped attaching member 6 is constructed from heavy wire and has one end bent to form an eye 7 that extends or fits in the eye 2 for the purpose of pivotally or swivelly connecting the attaching member 6 to the supporting element 1. The other end of the attaching member 6 is bent to form an elongated eye 8 adapted to receive the catch or hook 5 and owing to the pivotal connection between the attaching 70 member and the supporting element, said elongated eye 8 can be readily disengaged and engaged with the hook or catch. The attaching member 6 is provided with a comparatively straight portion 9 that extends at 75 right angles to the supporting element 1 and said attaching member then curves gradually outwardly and inwardly toward the supporting element before forming the elongated eye so that when the attaching 80 member 6 is passed through the opening in the shank of a ham 10, said ham will suspend from the comparatively straight portion 9 thereby preventing the elongated eye 8 from becoming detached from the hook or 85 catch.

While I have shown and described the preferred embodiment of my invention, it will be understood that minor changes in construction, combination, and arrangement 90 of parts may be made, without departing from the spirit and scope of the invention as claimed.

Having thus described my invention, what I claim is:—

95 A hanger of the class described having a rod section provided with an eyelet, an elongated portion extending therefrom, said section above the eyelet being formed into a suspending loop, the section from said 100 loop having coils disposed around the elongated portion to close the loop and then extending outwardly and upwardly into a hook, said coils also rigidifying the hook, a second section of substantially rigid material having an eyelet pivoting it to said first-named eyelet for vertical and lateral movement, the second section having a suspending portion and an elongated portion 105 extending therefrom, opposite the said first- 110

named elongated portion and the elongated portion of the second section having an elongated eyelet to engage said hook, said elongated portions extending on opposite sides 5 of a vertical line passing through the loop so as to support an article on the suspending portion in the line of the center of gravity.

In testimony whereof I affix my signature in presence of two witnesses.

JOSEPH VLACH, JR.

Witnesses:
